UNITED STATES PATENT OFFICE.

RICHARD W. BOND, OF WILMINGTON, DELAWARE.

CARTRIDGE-RELOADING TOOL.

Application filed April 1, 1927. Serial No. 180,194.

This invention relates to improvements in what is known as reloading tools or devices, the present device being adapted for use in decapping fired cartridges; sizing cartridges by contracting and expanding them; recapping said cartridges; and, inserting the bullet in the cartridge. The present tool is also adapted for use in sizing the bullet itself where the bullet is of over-size.

10 The present invention has for its object the provision of a tool of this character which is of simple construction or design so as to make it economical.

Another object is to provide such a tool 15 wherein the actual strokes for accomplishing the several steps in the reloading of the shells are of reduced length.

A further object is to provide a device 20 wherein the various tools for performing the several operations on the shells may be adjustably secured in place.

With these and other objects in view the invention consists in certain novel details of construction and combinations and arrangements of parts all as will hereinafter be more fully described and the novel features thereof particularly pointed out in the appended claims.

In the accompanying drawings,—

30 Figure 1 is a front elevation of a device embodying the present improvements.

Fig. 2 is a side elevation of the device equipped with tools for decapping fired cartridges.

35 Fig. 3 is a side elevation of the device equipped for contracting cartridges.

Fig. 4 shows the tool equipped for expanding cartridges.

Fig. 5 shows the tool for capping cartridges.

40 Fig. 6 illustrates the tool for inserting the bullets in the cartridges.

Fig. 7 is a side elevation showing the device arranged for reducing oversized bullets.

45 Stated generally, the tool consists of a frame having a slidably mounted plunger therein carrying an anvil which, in actual use, is adapted to be aligned with a suitable tool held in said frame for performing the necessary operations on the cartridge. For

50 this purpose the frame 1 has a socket 2 in which the tools are adapted to be held, and aligned with said socket 2 there is a second socket 3 in which is slidably held a plunger 4.

Plunger 4 has a slot 6 therein through which extends an operating lever 7 pivoted

in the frame on a pin 8, said lever engaging lugs 9 and 10 formed in the slotted portion of the plunger whereby when said lever 7 is rocked on its pivot the plunger will be 60 moved toward or from the socket depending upon the direction of movement of said lever. The device, which is portable, has lugs 11 formed integral with the frame so as to take an extended bearing on any suitable 65 support 12. The frame may be fixed to said support either by screws passing through orifices 13 in the lugs 11 or by a clamp 14 engaging over said lugs and extending beneath the supporting member 12 whose under surface is engaged by the ordinary screw of the usual clamp. Where the clamp is used the frame is adapted to have rigidity imparted thereto by reason of a vertically extended rib 15 formed thereon seating between two 70 corresponding ribs 16 formed on the clamp 14.

The end of plunger 4 nearest socket 2 is slotted as at 17 forming two arms 18 between which an anvil is adapted to be pivotally 80 supported by a pivot pin 19 as will herein-after appear. The anvil thus supported on the plunger 4 is limited in its rocking movement in one direction by a stop 30 formed on the frame and in the opposite direction 85 by reason of the anvil itself engaging the bottom of the slot 17.

When the device is used for decapping or ejecting used primers from shells an anvil 20 is pivoted at one end on the cross pin 19. 90

At its opposite end there is screwed on the anvil a nut 21 which carries a decapping pin 22. Preferably, the anvil 20 is formed in two sections, one section being pivoted on the pin 19 and adapted to have the other 95

section, which carries the decapping pin 22, screwed therein whereby the latter section is detachable so that sections of different sizes may be interchangeable to suit various sizes of cartridges. Screwed into the in-

ternally threaded socket 2 is the decapping and priming button 23, said button having a cavity 23^a therein providing space for the primers being ejected. A portion of the exterior surface of the decapping button 100

may be knurled so as to facilitate screwing it into the socket when it is being adjusted therein. The cartridge 24 to be decapped is placed over the anvil 20 with the decap-

ping pin 22 entering the flash hole as shown 105 in Fig. 2 and with the decapping button 23 adjusted in socket 2 just enough to al-

low only sufficient clearance space for the free passage of cartridges being swung into place, thus preventing the cartridges being positioned beneath the button except when 5 the decapping pin has been properly inserted in the flash hole. That is, with the decapping button projecting the proper distance from socket 2 if the decapping pin 22 is not positioned in the flash hole of the cartridge 10 then the cartridge will be positioned so high on the anvil 20 that it will not pass beneath the recessed end of the button when the anvil 20 is turned on its pivot 19 toward stop 30. After the assembly and adjustment of 15 the parts described and after the anvil 20 has been moved on its pivot into engagement with the stop 30, the cap of the cartridge is in registry with recess 23^a of the decapping button and by raising operating lever 20 7 the cartridge base will be seated against the decapping button. Then by applying additional force to the lever sufficient to continue the elevation thereof the used primer will be ejected from the cartridge into the 25 recess 23^a of button 23. The lever 7 is then returned to its former position and the anvil 20 moved on its pivot away from stop 30 to the position shown in full lines in Fig. 2, whereupon the decapped shell may be 30 readily removed. It will be noted that in this last movement of the anvil, away from stop 30, the lower end thereof engages the bottom of slot 17, as indicated at 25, to limit the tilting movement of said anvil.

35 It is well known that cartridges expand when they are fired making it necessary to resize the necks thereof before they are re-loaded and as the metal used in cartridges varies in thickness, the diameter of the neck, 40 which is the portion the bullet enters when being seated, should be first reduced and then expanded or resized with a standard expander. New cartridges can also be resized as hereinafter described, should it be 45 deemed advisable. The device prepared for thus reducing the diameter of the necks of cartridges is shown in Fig. 3 wherein a bushing 26, suitably threaded so as to be screwed into socket 2, is inserted in said 50 socket, the flange 26^a on said bushing being notched so that it can be tightened against the lower end of the socket. Said bushing is concentrically bored providing a neat sliding fit for the cartridges. Screwed into the 55 opposite end of socket 2 is a die 27, said die being formed with a knurled portion to facilitate its rotation when being adjusted in the socket. A nut 28 on the die 27 is 60 adapted to be tightened against the end of socket 2 after the die has been properly adjusted axially of said socket thereby locking the die in position. Die 27 has a central bore corresponding to the caliber of the shell used, the end of said bore nearest the bushing 26 serving to resize the cartridge as it is

pushed into the die. Adjacent the end of the die remote from bushing 26 the counterbore is somewhat enlarged for clearance. The end of the die adjacent the bushing is flared somewhat to facilitate entry of the end of the cartridge in the die.

In lieu of the anvil 20 utilized in decapping the cartridges, a different anvil 29 is pivotally mounted on the plunger 4, the free end of said anvil in this case being recessed to form a hook portion 31 which overlies the rim portion of rimmed cartridges or which may enter the groove in rimless cartridges. The end face of the anvil may also be provided with a recess 31^a, providing space for primers which may project somewhat from the base of the cartridge. After the parts have thus been assembled it is necessary to properly adjust the die 27, this being accomplished by first having the lock nut 28 loose and then inserting the cartridge through bushing 26 until it is seated against the flared mouth portion of the die. Lever 7 is then elevated, moving anvil 29 to the required height necessary for allowing the anvil to be swung against the stop 30 while at the same time the base of the cartridge is supported on the end of the anvil with the open end of the cartridge held against the flared open end of the die 27. During this adjustment, lever 7 should be held with sufficient force to keep the shell slightly pressed against die 27 while said die is being adjusted and when finally adjusted the space between the anvil head and the bushing 26 will be equal to the depth required for the shell to enter the die, this distance corresponding to the depth the bullet must enter the cartridge. Lock nut 28 is then tightened against the end of socket 2, thereby locking the die 27 in place and the sizing operation may then be carried on by lifting the operating lever 7 until the anvil head rests against bushing 26 thus providing the step for giving uniform resized length to any number of shells. While it is necessary to use a light force to pull a shell from the die this is taken care of by the hook shaped portion 31 formed on the anvil. After the cartridge has been sized by being projected into the die lever 7 is returned to its lower position at which time the cartridge will be removed from the die 27, while still held by bushing 26. The anvil is then swung on its pivot away from the stop 30 until its end engages the plunger at 25 whereupon the cartridge may be removed from the socket and the operation performed on as many successive cartridges as is desired.

The apparatus for expanding the necks of the cartridges is shown in Fig. 4. In this arrangement the bushing 26 and the anvil 29 are used as in the arrangement in Fig. 3. However, in the upper end of socket 2 there

is inserted a double adjustable tubular member 32 which has a suitable external thread to mesh with the thread in said socket. On said member 32 is a lock nut 28 which is 5 interchangeable with the die 27 in Fig. 3, said lock nut in this case serving to lock the double adjustable chamber 32 in the socket in the same manner as has been described for locking the die 27 in said socket in Fig. 3. 10 Tubular chamber member 32 has an inside finish suitably shaped to receive interchangeable parts, the upper end of said chamber 32 being of an enlarged bore to receive an adjusting screw 33 which serves as a stop for 15 holding an expander 34 in the reduced end portion of the bore in said member 32. The nut 35 with its periphery knurled is adapted to be screwed on the adjusting screw 33 and be tightened against the upper end of member 32 to lock said screw 33 in place. When 20 expander 34 is placed in member 32, it is adapted to seat against a shoulder 36 formed by the differences in the diameter of the bore in member 32 where it is held rigidly in 25 place by the adjusting screw 33. Said expander 34 has a pointed or conical end 37 which serves as a means for guiding cartridges on to the expander.

With the parts assembled as shown in 30 Fig. 4, final adjustment is made by having nut 28 loose and then inserting the cartridge through the bushing 26 until it is seated against end 37 of the expander. The anvil 29 is then swung into place against stop 30. 35 The parts are held in this position under a slight pressure while the double adjustable chamber 32 is screwed into or out of socket 2 until the space between the anvil head and bushing 26 is equal to the depth the bullet is 40 to be inserted in the cartridge. Lock nut 28 is then tightened so as to rigidly hold the expander 34 in this adjusted position. After 45 this has been done the anvil 29 is raised until it engages against bushing 26, thereby causing the open end of the cartridge to be 50 properly expanded. The lever is then returned to its original position thus relieving the cartridge and the anvil is then swung away from stop 30 so as to permit removal 55 of the cartridge from socket 2 and bushing 26.

The next step usually performed on the cartridges after they have been thus expanded or sized is to prime them or recap them. The device properly rigged for this 55 operation is shown in Fig. 5 wherein the decapping button 23 is inserted in socket 2 the same as in the arrangement shown in Fig. 2 for decapping the cartridge. The 60 decapping or priming button 23 is adjusted in socket 2 with its priming end 23^b arranged toward the anvil 20 which, in this case, is the same as used in decapping the cartridges. The protruding end of the button 65 is spaced from the anvil a sufficient dis-

tance to permit free passage of a cartridge being swung to position on the anvil 20. In the present case, however, the decapping pin 22, used in the arrangement shown in Fig. 2, is dispensed with, nut 21 only being 70 screwed on the free end of anvil 20. Formed in the end of the priming end 23^b of button 23 is a semispherical cavity which prevents flattening of the primers by having the points of contact between the button and primer located at points around the edge of the latter. In capping the cartridges the primer may be pressed into the cavity in the cartridge base with the finger sufficiently 75 far to make it stick either before or after 80 the cartridge is placed on the anvil 20.

With the parts assembled and the cartridge positioned on anvil 20 as shown in Fig. 5 and the primer inserted in the cartridge base the anvil 20 is moved to the position shown in dotted lines and the lever 7 is elevated until the primer is seated slightly against the priming end 23^b of the button 23. The lever 7 is then moved with sufficient force to press the primer into the cartridge after which the lever is returned to its original position and anvil 20 moved to its position shown in full lines of Fig. 5, to permit removal of the primed cartridge. 90

In Fig. 6 there is shown the device arranged for inserting the bullet in the cartridge. In this operation the parts used are the same as those used for expanding the cartridge, as shown in Fig. 4, with the exception of the expander 34 being dispensed with and a bullet seater substituted therefor. When used for this operation the bullet seater 38 is placed in the bore of the chamber member 32 and the parts adjusted with respect to the anvil 29 as in the case of the expanding operation. Said bullet seater has a cavity 39 in one end suitably shaped to receive the ends of the bullet without causing them to be marred and, in addition, this recess further provides a means for alining 100 the bullets. The entrance end 40 of the chamber member 32 acts as a guide for the cartridge as it is moved through said member 32 toward the recess end 39 of the bullet seater and at a point adjacent said recess 39 105 the inner wall of member 32 is formed with a shoulder 41 which provides for crimping the cartridges as the bullets come to the full depth of their insertion in the cartridge. 110

In assembling the parts for this operation the bullet seater 38 is placed in chamber member 32 and adjusting screw then turned down in said chamber, after which said chamber member is screwed down in socket 2. The positioning of these several parts 120 can be best accomplished with the use of a loaded cartridge. Such a cartridge can be inserted in socket 2 through bushing 26 and the anvil turned on its pivot to engage and support said cartridge, after which the 125 130

seater can be adjusted by turning the adjusting screw 33 until a slight pressure is transmitted to said anvil.

If it is desired to crimp the shell, these 5 adjustments should be made whereby the chamber member is so positioned in socket 2 that the anvil will be about one thirty-second of an inch from bushing 26 when it is operated with a shell in position. If it is 10 not desired to crimp the shell, the chamber member is so set that the shell does not come into contact with said crimping shoulder 41.

After these several adjustments have been 15 made, a shell to be loaded is placed with its open end over reamer 42 which is formed on the exposed end of screw 33 and twisted with sufficient force to make a slight counterbore therein thus providing a free entrance for the bullet. After the shell has thus been 20 made ready, a bullet is placed in the cartridge, base first, and the two inserted as a unit through the bushing 26. The anvil 29 is then brought against stop 30 while the operating lever is slightly lifted so that the 25 free end of the anvil will properly receive the base of the cartridge. Lever 7 is then elevated with sufficient force to move the anvil against bushing 26 with the result that 30 the bullet is pressed the proper depth in the shell. Lever 7 can then be lowered and the anvil 29 moved away from stop 30 to free the base of the cartridge.

Where the device is to be used for resizing 35 bullets it is fastened to a suitable support in an inverted position as shown in Fig. 7. In this instance the anvil 29, which is somewhat shorter than that used for decapping, is pivotally secured to the plunger 4 but in 40 the socket 2 there is inserted a bullet die 42 having a central bore of two diameters providing for an oversized bullet being inserted through the guide portion 42^a of said die until it is seated against the smaller diameter of the bore. Said small diameter has a cutting edge 42^b formed with a suitable recess 45 42^c adjacent thereto which serves as a space for chips while bullets are being forced through the die. The smaller diameter of the bore at 42^b is such that a bullet, if of 50 oversize, will be resized to the required standard as it is forced through the die. It will be noticed that there will be a natural tendency of the operating lever 7 to drop making it necessary to hold said lever up 55 while placing the bullets and bullet seater in the die. For this reason the operation of the device when used for the purpose of sizing the bullets is as follows: Operating lever 7 is held in a perpendicular position 60 and the anvil, or what might be termed the thrust bar is moved to the position shown in dotted lines in Fig. 7. While the parts are held in these positions die 42 is screwed 65 into socket 2 to a trial position, a bullet is placed, base first, in the die and the bullet

seater 38 is then inserted in the die with its recessed end resting on the pointed end of the bullet. The anvil or thrust bar is then turned to perpendicular position against stop 30 and lowered somewhat after which die 42 is adjusted in socket 2 to a position where there is only sufficient space between thrust bar and the enlarged end of the bullet seater to permit said bar being swung forward or backward. After the parts have been thus adjusted depression of the operating lever will force the bullet through the die 42 so that as it passes through the reduced bore of the die and out of socket 2 it will be reduced to the proper size.

For accurately centering the cartridge during the decapping and priming operations, there is a stop 30^a, preferably in the form of a screw threaded into the frame. Said stop 30^a can be adjusted to engage the 80 anvil 29, accurately center the cap with the priming button, and, when such accuracy is not needed; as in the other operations, said stop can be screwed further into the frame so as not to engage said anvil.

What I claim is:

1. In a device of the character described, the combination of a support for the cartridge, a support for interchangeably receiving tools for performing the desired operations on the cartridge, and means for moving said cartridge support toward and from the tool support, said cartridge support being pivoted to permit a cartridge carried thereby to be moved into and out of registry with a tool in said tool support.

2. In a device of the character described, the combination of a support for the cartridge, a support for interchangeably receiving tools for performing the desired operations on the cartridge, and means for moving said cartridge support toward and from the tool support, said cartridge support being pivoted to permit a cartridge carried thereby to be moved into and out of registry with a tool in said tool support, and stops for limiting rocking movement of said cartridge support.

3. In a device of the character described, the combination of a frame having a support in which tools for performing the desired operation on a cartridge may be interchangeably received and adjustably supported, an anvil on which a cartridge is supported, said anvil being pivotally supported on said frame, a stop for limiting rocking movement of said anvil to center the cartridge with respect to said tool, and means for effecting a relative movement of cartridge and tool supports.

4. In a device of the character described, the combination of a frame having a support in which tools for performing the desired operation on a cartridge may be interchangeably received and adjustably sup-

ported, an anvil on which a cartridge is supported, said anvil being pivotally supported on said frame, a stop for limiting rocking movement of said anvil to center the cartridge with respect to said tool, a stop for limiting pivotal movement of the anvil in the opposite direction, and means for moving the cartridge support toward and from the tool support.

10 5. In a device of the character described, the combination of a frame having spaced aligned sockets formed therein, a plunger slideable in one socket, an anvil detachably supported on said plunger, means for moving said plunger and anvil toward and from the other socket, and means for interchangeably receiving and supporting a desired tool in said other socket.

6. In a device of the character described, 20 the combination of a frame, a plunger slidably mounted in said frame, an anvil carried by said plunger for supporting the cartridge, a decapping pin adjustably fixed

on said anvil and adapted to engage the cap of the cartridge on said anvil, means on a 25 fixed portion of said frame for supporting a decapping button, and means for moving said plunger together with the anvil toward and from the decapping button.

7. In a device of the character described, 30 the combination of a frame, a plunger slideable in said frame, a cartridge supporting anvil pivotally mounted on said plunger, a decapping pin adjustably carried on said anvil and engaging the cap of a cartridge 35 supported on the anvil, a recessed decapping button adjustably secured in a fixed portion of said frame, means for limiting the pivotal movement of the anvil for centering the cartridge with respect to the button and 40 alining the cap of said cartridge with the recess in said button, and means for moving said plunger and anvil toward and from said button.

RICHARD W. BOND.
